(57) **CLAIM**

The ornamental design for a work light as shown and described.

DESCRIPTION

FIG. 1 is a first top perspective view of a work light according to one embodiment.

FIG. 2 is a first bottom perspective view of the work light of FIG. 1.

FIG. 3 is a second top perspective view of the work light of FIG. 1.

FIG. 4 is a second bottom perspective view of the work light of FIG. 1.

FIG. 5 is a first side view of the work light of FIG. 1.

FIG. 6 is a second side view of the work light of FIG. 1.

FIG. 7 is a front view of the work light of FIG. 1.

FIG. 8 is a rear view of the work light of FIG. 1.

FIG. 9 is a top view of the work light of FIG. 1.

FIG. 10 is a bottom view of the work light of FIG. 1.

FIG. 11 is a first top perspective view of a work light according to another embodiment.

FIG. 12 is a first bottom perspective view of the work light of FIG. 11.

FIG. 13 is a second top perspective view of the work light of FIG. 11.

FIG. 14 is a second bottom perspective view of the work light of FIG. 11.

FIG. 15 is a first side view of the work light of FIG. 11.

FIG. 16 is a second side view of the work light of FIG. 11.

FIG. 17 is a front view of the work light of FIG. 11.

FIG. 18 is a rear view of the work light of FIG. 11.

FIG. 19 is a top view of the work light of FIG. 11; and,

FIG. 20 is a bottom view of the work light of FIG. 11.

(Continued)

The broken lines in the drawings depict portions of the work light which form no part of the claimed design.
